UNITED STATES PATENT OFFICE.

PHILIP MUELLER, OF DÉCATUR, ILLINOIS, ASSIGNOR TO H. MUELLER MANUFACTURING COMPANY, OF DECATUR, ILLINOIS, A CORPORATION OF ILLINOIS.

CESSPOOL.

1,033,448.

Specification of Letters Patent. Patented July 23, 1912.

Application filed October 18, 1911. Serial No. 655,320.

To all whom it may concern:

Be it known that I, PHILIP MUELLER, a citizen of the United States, residing at Decatur, in the county of Macon and State of Illinois, have invented new and useful Improvements in Cesspools; of which the following is a specification.

My invention relates to a cesspool for floor use, and particularly to one adapted for use in the operating rooms of hospitals. It is very desirable and in some cases essential that such floors be well drained and that they should be so constructed and equipped as to be easily and readily cleaned and placed in first-class sanitary condition. At the present time the floors are commonly made sloping toward a certain point from which a drain pipe leads, this drain pipe being usually equipped with a strainer sometimes flush with the floor and sometimes not, for preventing the drain pipe from becoming clogged by solid substances. It frequently happens, however, that this strainer is broken, displaced and lost with the result that the drain pipe thus becomes clogged and soon reaches an unsanitary condition. Further trouble is experienced with these drain pipes as commonly installed owing to the fact that their inlet ends at the floor are located some distance away from the trap, the trap being often times located eight or ten feet away from the opening and adjacent the delivery of the pipe into the sewer. In such cases particularly when the drain pipe is substantially horizontal or has little slope, the drainage of the pipe is not complete and that portion of it which adheres to the walls of the pipe is added to at each draining of the floor and the pipe soon reaches an unsanitary condition, obnoxious and unpleasant gases being emitted to the room through the open end of the pipe. A similar condition is often found when the discharge pipe instead of being led to a sewer is led to other point of discharge and is without traps of any kind.

The object of my invention is to produce a cesspool for hospitals, by the use of which the above named troubles may be avoided. The cesspool which I have invented wholly avoids these troubles, and is possessed of many advantages which make it an efficient and valuable product.

My invention consists of a floor basin adapted to be placed in a floor and fit with

its upper edge flush with the surface of the floor. This basin I construct of ample proportions which, of course, may be varied according to the size of the floor or the size of the drain pipe to be used in connection with it. Just at the bottom of the basin and contiguous to it I provide a trap which communicates directly with the basin. The escape into a room of obnoxious gases from the section of the drain pipe leading to the sewer, as well as gases from the sewer, is thus effectually prevented. By locating this trap contiguous to the basin I especially adapt it for floor use as there is not room in most instances owing to the small space between ceiling and superposed floor in most building constructions to properly locate a trap with respect to a drainage basin in any other manner. Within the basin above the trap opening but below the surface of the floor, I provide a strainer. By virtue of its position within the basin there is no danger of its being displaced accidentally. An attached cover of special construction fits the top of the basin snugly and covers the cesspool and its parts when not in use, the top of the cover being flush with the surface of the floor. This cover is locked down tightly by a special locking mechanism which is beneath the cover, but which is adapted to be operated from the outside by a suitable key which I prefer to connect with the mechanism and cover and make flush with the top of the cover. Thus when the cover is in place it forms a part of the floor, and there is no projection above it which might be in the way.

The full advantages of my improved cesspool together with the various details of construction thereof, will be readily apparent from the following description taken in connection with the accompanying drawings, in which—

Figure 1 is a central sectional elevation of the same equipped with one form of cover locked in place. Fig. 2 is a similar view, showing the cover in raised position and the mouth of the cesspool open. Fig. 3 is a view of the underneath side of the cover showing the hinge and lever connections. Fig. 4 is a detail of the locking key, and its connection to the locking levers. Fig. 5 is a view of the underneath side of the strainer I use. Fig. 6 is a sectional side elevation of the same. Figs. 7 and 8 are plan and sec-

tional elevation respectively, of a modified form of locking means for use with the cover, and Fig. 9 shows in section a modified form of locking key whose upper end is 5 flush with the top of the cover.

Referring to the drawings, 10 is a basin of my improved cesspool. This basin is made up of a floor flange or ring 11 adapted to fit flush with the floor to be drained, and 10 depending therefrom is a basin proper in the body of which are formed a plurality of shelves 12, 13, and 14. Preferably these shelves are formed concentric with each other and with the floor ring 11, and within 15 the lowermost shelf 14 is formed a concentric opening 15.

From the lowermost shelf 14, and projecting through the opening 15 is a main body 16 of the trap. This main body makes a 20 tight joint with the shelf 14, solder 17 being used for this purpose, and in the side of the main body some distance above its bottom is a discharge opening 18; this discharge opening, of course, I may locate as I find 25 most desirable.

Supported from the shelf 13 by means of its flange 19 is a sectional member 20 of the trap which is preferably concentric with the main body and does not reach quite to its 30 bottom, but does reach below the discharge opening 18. The drainage which enters the trap, therefore, passes through the member 20 and the water seal which is formed in the main body, and whose level is the lower wall 35 of the discharge opening, and then passes through the discharge opening to the sewer. The white leaded joint is made between the member 20 and the shelf 13, a concentric tongue and groove 21 being formed between 40 the flange 19 and the shelf 13, and screws 22 being used to firmly screw the member 20 in place. By the simple removal of the screws 22, however, the member 20 may be removed from within the basin, and free access 45 can be had to the main body of the trap or the sewer for cleaning the same.

The shelf 12, which is the uppermost of the three shelves 12, 13 and 14, carries a strainer 23. This strainer I prefer to make 50 in the form of a plate as shown, the plate being cast or otherwise made in the shape shown in Figs. 5 and 6, and provided with a plurality of tapering holes, the walls of the hole forming in outline a frusto-conical figure, and the small ends of the holes all lying on one side of the plate. This strainer I 55 position within the basin of the cesspool, as shown in Figs. 1 and 2, a side of the plate with the small ends of the holes being the top of the strainer. I find that when so formed and used this strainer is most sanitary. The drainage passing through the strainer falls from it and unobstructed 60 through the large ends of the straining holes. 65 There is thus but little tendency for drain-

age to accumulate on the walls of the holes, as it does not under ordinary conditions touch them. Such little, however, as does accumulate, is on the under side of the strainer and not exposed to view, as would 70 be the case if the holes were tapered in the opposite direction, and the strainer thus presents a cleanly appearance at all times. It will be noted that this strainer simply rests upon the shelf 12 by gravity, and it may 75 thus be removed at will for cleansing it and for cleansing the underneath portions of the basin.

As thus constructed the cesspool is complete as far as is necessary for it to perform 80 its functions as a cesspool. I prefer, however, to provide the cesspool with a cover, which fits flush with the surface of the floor and hides the pool from view as well as prevents the receipt of foreign matter by it, 85 when it is not in use. This cover is indicated at 24. A hinge link 25 is hinged at one end to a lug 26 within the mouth of the basin and at the other end to a lug 27 depending from the under side of the cover 90 24 and approximately at its center. The link 25 is preferably formed in an H-shaped form as clearly shown in Fig. 3. The cover is ribbed on its under side in order to strengthen it, five or six ribs 28 being shown 95 for this purpose, and one of them 29 is cut away to accommodate the cross-bar 30 of the link member 25 when the cover is in closed position. Also hinged to the lug 27 is a locking lever 31 for locking or clamping 100 the cover in place, this lever extending to the side of the basin and bearing at its outer end against a lug 32. Short of this end it has formed within it a hole 33 through which passes a clamping screw 34 which 105 enters a screw threaded cavity 35 in the body of the basin and is provided with a thumb-piece 36 on its upper end. This screw or bolt is provided at its upper end with an enlarged portion 36' which bears 110 against the upper side of the locking lever 31, the large portion being of too great diameter to pass through the hole 33. When the screw is turned by the thumb-piece right-handedly it travels downwardly, and bearing against the upper side of the locking lever 31 turns it about the lug 32 as a fulcrum and brings pressure to bear on the lug 27 on the under side of the cover, thus locking it in place. Preferably the edges 37 115 of the cover and the coöperating edge of the basin are beveled as shown, and as the lug is approximately in the center of the cover a firm even pressure is brought to bear and a close tight joint of the cover with the basin 120 secured. When it is desired to open the pool for use the screw 34 is simply turned until it is released by the screw threads at its lower end and thereafter the cover may be 125 swung upward and backward on its link 25, 130

the position of the parts being as shown in Fig. 2. As the cover is secured to the basin by the link 25 it is always in place, and there is no danger of its being lost. The peculiar shape of the link 25 gives great stability and keeps the cover accurately in alignment.

The screw 34 forms what I term the key of my locking device properly. I so associate this key with the cover and locking lever that it cannot be readily removed therefrom. To this end I use a set screw 34' as shown in Fig. 4 which passes through the body of the locking lever 31 and engages a screw at its reduced portion above the screw threads at its end. Preferably also I do not use a thumb-piece 36 as shown in Fig. 1, as this may often times be in the way, and is likely to cause a person to stumble, but use a screw having a head flush with the top of the cover, as shown in Fig. 9. In this construction the top of the cover is countersunk to receive the retaining flange 38 formed on the top of the screw and a slot 39 is provided for the operation of the key by a screw driver or other suitable tool, as such a tool is nearly always at hand or can be easily provided. This form of key is almost as convenient for operation as the form shown in Fig. 1, and possesses the advantage that it is entirely out of the way and presents a much neater appearance. There is also less likelihood of the accumulation of dust and dirt around it. In connection with the screw threaded cavity 35 with all forms of keys I provide an outlet 22* which communicates with the bottom of the cavity, for the purpose of expelling from the cavity any contents which it may have received during the use of the cesspool. When the keys are forced home these contacts are expelled through the opening 22* into the body of the pool.

In Figs. 7 and 8 I have shown a modified form of locking means for the cover. This consists of a simple diametrically placed cross bar 40, which is preferably located below the strainer 23, as shown, being screwed down at its ends to a shelf 12, of the basin, which is formed to accommodate it. At the center of the bar is formed a screw threaded hole 41, which accommodates the end of a clamping screw 42 which passes centrally through the cover and through the strainer, its slotted head being flush with the top of the cover, as in the case of the keys for I prefer to associate this screw with the cover by securing it thereto. To this end I pass a pin 42' through the body of the screw just below the cover. This prevents the screw being removed and lost. In some instances I may locate the transverse bar above the strainer, but I prefer to locate it below the strainer for the reason that the basin is then more

easily cleaned, and presents a neater appearance.

What I claim is:

1. In combination with a floor flange, a cover for the same, a connecting element hinged at one end to the underside of the cover and at its opposite end to the flange, a locking lever hinged to the underside and at the central portion of the cover and resting at its free end upon one side of the flange, and a clamping member carried upon said locking lever adjacent to its free end and engaging the flange whereby said locking lever is drawn down into the plane of the flange to bind said cover upon the same. 70

2. In combination with a surface flange having an opening therethrough, a cover adapted to fit in the opening, a pair of toggle links hinged to the underside of the cover, one of the links having pivotal connection to one side of the flange and the opposite link being adapted to engage at its outer end against the opposite side of the flange whereby to provide a fulcrum for the toggle links, and a binding screw carried through the cover and through the opposite link at a point spaced inwardly from its free fulcrumed end, said flange having a threaded opening beneath the cover, said screw being adapted for threaded engagement in the opening whereby said toggle links are drawn down into the plane of the flange to bind the cover in the opening. 85

3. In combination with a surface flange having a central opening therethrough and a depressed shoulder about the inner marginal edge of the opening, a cover fitting into the opening, a hinge link pivoted at one end of said shoulder of the flange and at its opposite end to the underside and central portion of the cover, a locking lever hinged at one end to the cover at its central portion and being adapted to engage the shoulder of the flange at its free end and at a point diametrically opposite to the connection of the hinge link to the shoulder, and a clamping screw carried upon the locking lever adjacent to its free end and engaging in the shoulder whereby to draw said locking lever down into the plane of the flange and bind said cover in the opening. 100

4. In combination with a floor flange having a central opening and diametrically opposed lugs projecting inwardly from the marginal edge of the opening, a cover fitting in the opening, a hinge link hinged at one end to one of the lugs and at its opposite end to the underside of the cover at its central portion, a locking lever hinged to the underside of the cover at its central portion and having its free end adapted to bear against the opposite lug, and a clamping screw carried by the outer end of the locking 110

lever and adapted to engage in the lug whereby to draw said locking lever down at its hinged end and bind said cover in the opening.

5. In combination with a drain, a cover for the same comprising a lug on the inside of the drain mouth, a locking lever connecting at one end to the underneath side of the cover, and at the other end bearing on said lug, and means for acting on said lever from the outside of the cover to turn the lever about the lug as a fulcrum to lock said cover in place.

6. In combination with a drain, a cover for the same comprising a lug on the inside of the drain mouth, a locking lever connecting at one end to the underneath side of the cover, and at the other end bearing on said lug, and means comprising a screw for acting on said lever from the outside of the cover to turn the lever about the lug as a fulcrum to lock said cover in place.

7. In combination with a floor flange, a cover for the flange, a toggle member having the meeting ends of its links hinged to the underside and at the central portion of the cover, one of the links having hinged connection with one side of the flange and the free end of the opposite link being adapted to bear against the opposite side of the flange, and a clamping member associated with said toggle member and engaging said flange whereby to expand said toggle member and draw the cover down over the flange.

its opposite end upon the opposite side of the flange, said toggle member having 40 hinged connection at its central portion to the underside of the cover, and means for expanding said toggle member whereby said cover binds within the flange.

9. In combination, a cover member to be 45 secured to another member, and a toggle link securing means therefor on the inside of the cover and connected with the cover and adapted to connect with the member to which the cover is secured, and means for 50 expanding said toggle to secure the cover member in place.

10. In combination with a floor flange, a cover for the same, said flange having diametrically opposed lugs located at its inner 55 marginal edge, a toggle member hinged at one end to one of the lugs and adapted to engage at its opposite end upon the opposite lug, said toggle member having hinged connection to the underside of the cover at its 60 central portion, a clamping member carried in the outer end of the toggle member and engaging said opposite lug whereby said toggle member is expanded to bind said cover upon the flange, said clamping member extending up through said cover whereby 65 said toggle may be operated from above the cover.

In testimony whereof I have hereunto set my hand in presence of two subscribing 70 witnesses.

PHILIP MUELLER.
